UNITED STATES PATENT OFFICE.

GEORGE W. START, OF PORTLAND, OREGON, ASSIGNOR OF ONE-HALF TO GEORGE KINNEAR, OF PORTLAND, OREGON.

OIL BURNER.

Application filed May 23, 1925. Serial No. 32,351.

To all whom it may concern:

Be it known that I, GEORGE W. START, a citizen of the United States, residing at Portland, in the county of Multnomah and 5 State of Oregon, have invented certain new and useful Improvements in Oil Burners, of which the following is a specification.

My invention relates to certain new and useful improvements in oil burners of the 10 type adapted to the use of crude oil fuel, and it is the object of this invention to provide a burner of a simple and effective construction which may be used without motors and pumps, which will not readily clog, and 15 which, should it become clogged, may be readily cleaned without dissembling the structure and without the use of special tools or cleaning implements.

The invention resides in those novel 20 features of construction, combination and arrangement of parts, which will herein-after be described, and then be specifically pointed out in the appended claims, reference being had to the accompanying drawing, in which:

Figure 1 is a longitudinal section of a burner constructed in keeping with my invention.

Figure 2 is a detail front elevation of 30 the nozzle.

In the drawing, in which like numerals of reference designate like parts in all the figures, 1 is the pipe line from the oil reservoir or tank (not shown). 2 is the oil 35 throttle valve, 3 the combined steam and oil throttle valve and 4 the steam jacket pipe connecting the valves 2 and 3.

5 is the oil feed duct located within the pipe 4, one end of the duct 5 being welded 40 to the pipe to form a cutoff therein, while the other end is left open as shown.

6 is the steam inlet connection to the pipe 4, and 7 is the throttle valve which controls the admission of the steam to the 45 inlet 6.

8 designates a T which is connected by a pipe 9 with the valve 3 and to which is connected the duct 10 through which the combined vaporized oil and steam are 50 passed to the nozzle or burner tip.

12 is the steam outlet of the nozzle 11 and 13 is an oil baffle thereof which delivers the vaporized oil and steam issuing from the nozzle down across the path of the ejector-steam issuing from the outlet 12 of the 55

nozzle. The mixture of vaporized oil and steam passes out of the opening 14 of the nozzle 11.

16 is a steam control throttle valve through which steam flows to an auxiliary 60 steam duct 15 that is located within the pipe 10 and delivers steam to the inner chamber 18 of the nozzle to issue through the opening 12 thereof.

In using my invention the oil tank need 65 not be located at a higher level than the burner which is preferably located below the fire box of the furnace. When steam is admitted through the valve 7 and after the valves 2 and 3 are opened the steam will 70 pass around the pipe 5, through valve 3, T 8, pipe 10 to the outer chamber 17 of the nozzle or tip 11 and out through the opening 14. As the steam passes the forward or free end of the pipe 5 it creates 75 a partial vacuum or suction there and draws oil from the tank through the pipe line 1 and valve 2 into the pipe 5 from which it issues and is mixed with the steam before entering the valve 3, thereby atomizing the oil 80 and mixing it with a quantity of the steam. This atomized mixture then passes through valve 3, pipe 9, T 8, into pipe 10 where it 85 surrounds pipe 15 and encounters the heat therefrom, thereby preventing condensation as the mixture passes through the pipe 10.

As the mixture of atomized oil and steam passes out of the nozzle 11 it travels down in front of the port 12 where it encounters the ejected steam from the inner chamber 90 18 of the nozzle and is there further atomized and ejected into the combustion chamber of the furnace. Thus it will be seen that by my construction the oil undergoes a primary breaking up (atomization) 95 on leaving pipe 5 and entering valve 3, and a final or auxiliary breaking up or atomization as it leaves the nozzle 11 and encounters the ejector-steam jet issuing from the port 12. Thus the oil is thoroughly 100 atomized and mixed with the steam vapors before entering the fire box and a more perfect combustion (consequently less production of smoke) is had than with other burners such as are in common use.

Should it be found desirable to clean the burner, if it be clogged forwardly, i. e. in the tip or nozzle end, it is only necessary to close the valve 2 and open the valves 3 and 7, whereupon the steam will scavenge the 110

burner thoroughly, blowing out the débris through the opening 14; if the oil line be clogged it is only necessary to close the valve 3 and open the valves 2 and 7 to cause the steam to force the contents back into the tank from whence it came.

Should the oil get thick as in cold weather, it can be heated in the tank and the pipe line heated simply by closing the valve 3 and opening valves 2 and 7, blowing back the oil in the pipe and admitting steam into the pipe line and oil tank.

The advantages of my invention, it will be seen, reside principally in the facts that (1), there is a saving of installation costs over those systems using motors or pumps; (2) the burner may be readily cleaned without being shut down and taken apart; and (3) a breaking up and atomizing of oil on entering valve 2 which continues onto the tip and is treated to a second atomization at the place of egress from the tip causing a supply of oxygen to be mixed with the oil at the place where the steam first mixes with it and an additional supply as the mixture leaves the burner tip, thus resulting in practically perfect combustion in the combustion chamber.

From the foregoing description, taken in connection with the accompanying drawing, it is thought the construction, operation and advantages of my invention will be clear to those skilled in the art to which it appertains.

What I claim is:

1. In crude oil burners, an oil line, an oil throttle valve to which the same leads, a second throttle valve, a jacket pipe connecting said throttle valves, an oil feed pipe located within said jacket pipe and secured at one end within the same to form an annular chamber and to receive the oil from

oil throttle valve and deliver it into said jacket pipe at a place remote from said oil throttle valve, a steam inlet duct with a primary steam valve for delivering steam into said jacket pipe at a place adjacent said oil throttle valve, whereby the oil and steam will mix on entering said second throttle valve, a burner nozzle, a pipe connecting said second throttle valve with said nozzle to deliver the mixture thereto, and means for delivering and ejecting streams of steam from said nozzle to engage the mixture as it issues from the nozzle and further vaporize the oil and deliver the mixture to the place for combustion.

2. In crude oil burners, an oil line, an oil-throttle valve to which the same leads, a second throttle valve, a jacket pipe connecting said throttle valves, an oil feed pipe located within said jacket pipe and secured at one end within the same to form an annular chamber and to receive the oil from said oil throttle valve and deliver it into said jacket pipe at a place remote from said oil throttle valve, a steam inlet duct with a primary steam valve for delivering steam into said jacket pipe at a place adjacent said oil throttle valve, whereby the oil and steam will mix on entering said second throttle valve, a burner nozzle, a pipe connecting said second throttle valve with said nozzle to deliver the mixture thereto, an auxiliary steam duct controlled by a separate steam throttle valve and passing through said pipe which delivers the mixture to the nozzle, said nozzle being connected with said auxiliary steam duct whereby to deliver the steam against the mixture as it issues from the nozzle to effect further atomizing of the oil and to deliver same to the place for combustion.

GEORGE W. START.
